ART OF CANDLE MAKING

Alois L. Berger, Oshkosh, Wis.

Application May 20, 1931. Serial No. 538,679

2 Claims. (Cl. 18—27)

This invention relates to improvements in the art of candle making, and specifically to an apparatus for making wax and tallow candles.

A general object of the invention is to provide a simple and efficient instrumentality for effecting commercial exploitation of the method of forming, in a finished manner, a plural number of candles in one operation.

Most forms of candles are provided with 10 tapered and fluted lower extremities whereby the candles may be inserted and retained in candle holders and held vertically for use. Heretofore, the formation of the tapered, fluted end portion of a candle has presented a difficult 15 problem and in most of the prior, commercially practical candle making mechanisms it was necessary to first completely cast the candle, and to then remove the candle from its mold and machine the end of the candle to form the tapered, fluted portion thereof.

As a more specific object of the invention, the present device permits the satisfactory, expedient casting of a candle so that when the candle is removed from its mold it is in a finished condition formed with the tapered fluted end portion, and no more operations are required on the candle.

A further object of the invention is to provide 30 a candle mold having means for positively centering and alining the candle wick so that in the finished candle the wick will extend correctly centrally through the candle.

A further object of the invention is to provide 35 a device for forming candles which is very simple, which is inexpensive and is expedient, and is well adapted for the purpose set forth.

With the above and other objects in view, the invention consists of the improved device for 40 forming candles, and its parts, steps and combinations, as set forth in the claims, and all equivalents thereof.

In the accompanying drawing in which the same reference characters indicate the same parts in all of the views:

Fig. 1 is a longitudinal vertical sectional view 45 through the improved candle mold;

Fig. 2 is a plan view thereof;

Fig. 3 is a transverse vertical sectional view 50 taken on line 3—3 of Fig. 1; and

Fig. 4 is a front view of the candle mold.

Referring now more particularly to the drawing, it will appear that the improved candle mold includes a two-part elongated major portion formed of a pair of complementary hinged-together plate members 8, mounted upon suit-

able supporting legs 9. The plate members 8 are formed with complementary candle forming semi-circular vertically extending recesses 10. The lower portions of the recesses 10 are somewhat reduced and rounded and tapered, as at 60 11, and said portions of the molds from the upper ends of the finished candles formed in the molds. Below each portion 11 grooves and notches 12 are formed in one of the mold plates 8.

There is removably positioned on the upper end portion of the complementary mold sections 8 an end forming mold bar 13. Said mold bar 13 is not of split formation and has extending therethrough in spaced apart relation, tapered and ribbed recesses 14 which register with the complementary recesses 10 in the mold sections 8. Said tapered and ribbed recesses 14 are arranged to form on the ultimate ends of candles tapered and fluted lower ends. The end forming mold bar 14 is removably held in position on the members 8, with the openings 14 in registration with the recesses 10 by means of depending pins 15 which extend into recesses therefor in the top portions of the mold sections 8.

The inner end portion of the mold bar 13 carries an upstanding hinge pin 16 on which is hingedly mounted inner end portions of a complementary split or two-part top mold section 17. The sections of the mold part 17 form in 85 their enclosed relation a funnel-like cavity designated by the numeral 18, and the bottom wall of said cavity is provided with a plurality of spaced apart relatively small circular openings 19 which register with the upper ends of the openings 14 in the mold bar 13. An upper edge portion of one of the sections of the mold member 17 carries spaced apart upstanding binding posts 20.

When the mold is to be used for forming a 90 plurality of candles, the requisite number of wick-forming strings 21 are provided, one for each candle to be formed by the mold. Each wick-forming string has its lower end portion 100 knotted and engaged within a notched portion 12 at the lower end of the mold sections 8. Each string is then drawn vertically centrally through recesses 10, 14 and 19 and through a centering projection 22 carried by a binding post 105 and then the upper end of each wick-forming string is tightly clamped in taut condition by the adjacent binding post 20, as shown.

The front end portions of the mold sections 8 carry complementary lugs 23 and clamping bolts 110 24. Also, the sections of the upper mold mem-

bers 17 carry similar lugs 25 and a clamping bolt 26. Said lugs and clamping bolts permit the mold sections to be tightly clamped together in enclosure forming relation, and of course the 5 mold bar 13 is positioned between the mold members 8 and 17, as shown. Molten wax or tallow is poured into the upper end of the mold through the funnel-like cavity 18 and said molten material, of course, gravitates through the various 10 openings and recesses and completely fills all of the cylindrical recesses 10 and the tapered fluted recesses 14. After the pouring operation, the mold may be immediately immersed in cold water to cool the candle material. The top section 15 17 is next opened and the ends of the wick strings 21 may be cut or severed from the binding posts 20. The next step is to lift the mold bar 13 vertically from the mold sections 8 whereby the mold bar 13 becomes removed from 20 and frees the fluted tapered end portions of the formed candles. Lastly, the main mold sections 8 are released and opened with respect to one another and the completed candles may then be removed from the molds. In Figure 1 the 25 last mold to the right therein shows a completed candle, and it is to be noted that a candle is thus formed in one single casting operation, practically in its final condition, and that the wick 21 therein is positively centralized with respect to all portions of the candle and especially the ends thereof. Also, the tapered fluted lower end of the candle is formed on the candle and during the casting operation. If necessary, the 30 ends of the wicks projecting from the upper and lower ends of the candles may be accurately trimmed.

From the foregoing description, it will be seen that the present invention provides a very simple candle mold for completely forming therein a plural number of candles, the candle mold provides for the formation on the candles of the desired tapered fluted ends and also insures positive centralizing of the wicks in the candles. 45

The mold is so arranged that the casting of candles therein is extremely simple and expeditious and is commercially practical.

What is claimed as the invention is:

1. A candle mold comprising, a main mold having a plurality of substantially cylindrical cavities therein, said mold being split into complementary sections along a plane disposed longitudinally and centrally of said cavities, means for clamping said sections together, a one-piece bar having annular projections at one side interlocking with the ends of said sections concentrically with said cavities and also having tapered ribbed through openings, the larger ends of which register with the ends of said cavities, a distributing trough split along said plane and coacting with the opposite side of said bar, said trough having restricted discharge holes communicating with the smaller ends of said tapered openings, and means for holding a wick centrally within each set of said holes, openings and cavities. 30

2. A candle mold comprising, a main mold having a series of parallel cylindrical cavities therein, said mold being split into complementary sections along a plane disposed longitudinally and centrally of said cavities, means for pivotally connecting and for clamping said sections together, a one-piece bar having a series of integral annular projections interlocking with the ends of said sections concentrically with said cavities and also having tapered ribbed through openings, the larger ends of which are within said projections and register with the ends of said cavities, a distributing trough split along said plane and coacting with the opposite side of said bar, said trough having a series of restricted discharge holes communicating with and centralized relative to the smaller ends of said tapered openings, and means for releasably holding a wick centrally within each aligned set of said holes, openings and cavities. 100
